US00D551017S

(12) **United States Design Patent** (10) **Patent No.:** **US D551,017 S**
Beesley et al. (45) **Date of Patent:** **** Sep. 18, 2007**

(54) **TOASTER**

(75) Inventors: **Brian K. Beesley**, Draper, UT (US); **Eric Hales**, Ogden, UT (US); **Liao Zhiwen**, Foshan (CN)

(73) Assignee: **Back to Basics Products, Inc.**, Bluffdale, UT (US)

(**) Term: **14 Years**

(21) Appl. No.: **29/251,614**

(22) Filed: **Jan. 9, 2006**

(51) **LOC (8) Cl.** **07-02**

(52) **U.S. Cl.** **D7/330**

(58) **Field of Classification Search** D7/323, D7/328-333, 385, 390, 340, 341, 346, 365, D7/367, 402, 405, 406, 407, 411; D13/158, D13/162, 162.1, 163; D21/525; 99/331, 332, 99/357, 375, 385; 219/214, 388, 405, 443.1, 219/450.1, 492

See application file for complete search history.

(57) **CLAIM**

The ornamental design for a toaster, as shown and described.

DESCRIPTION

FIG. 1 is a front, right perspective view of the toaster in accordance with our invention;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in FIGS. 1-7 are for illustrative purposes only and form no part of the claimed design.

1 Claim, 4 Drawing Sheets
